UNITED STATES PATENT OFFICE.

DANIEL WILDE, OF WASHINGTON, IOWA.

GRAIN-ELEVATOR.

SPECIFICATION forming part of Letters Patent No. 442,159, dated December 9, 1890.

Application filed July 24, 1889. Serial No. 318,537. (No model.)

To all whom it may concern:

Be it known that I, DANIEL WILDE, a citizen of the United States, residing at Washington, in the county of Washington and 5 State of Iowa, have invented a new and useful Grain-Elevator, of which the following is a specification.

This invention relates to grain-elevators adapted to be used in combination with 10 thrashing-machines or separators; and it has for its object to so construct the elevator that it shall raise the grain to such a height that it may be discharged directly into a wagon when desired.

15 The invention further consists in certain improvements in the detailed construction of the device, which will be hereinafter fully described, and particularly pointed out in the claims.

20 In the drawings hereto annexed, Figure 1 is a vertical sectional view of my improved grain-elevator. Fig. 2 is a sectional view taken through the bagging-spout on the line $x\ x$ in Fig. 1. Fig. 3 is a vertical sectional 25 view illustrating a modification in the construction of my improved elevator, and Fig. 4 is a side elevation showing a portion of a thrashing-machine to which the elevating device shown in Fig. 1 has been applied.

30 Like numerals of reference indicate like parts in all the figures.

My improved grain-elevator comprises, primarily, a rectangular tubular frame 1, at the four corners of which are mounted sprocket-wheels 2, supporting the endless chain 3, to 35 the links of which are attached the bucket-plates 4. The latter are fitted accurately in the tubular legs of the frame 1, so that when the endless chain is in operation the said 40 bucket-plates shall carry the grain along through the said frame.

The rectangular frame 1 is made of such size and shape as to fit completely around the frame of a thrashing-machine, and the 45 lower end of said frame 1, which is open on top, is arranged directly below the grain-board of such thrashing-machine, so as to receive the grain as the latter is separated from the straw and chaff.

50 Motion may be imparted to the elevating mechanism from the driving mechanism of the thrashing-machine by means of a belt or

band, which may be run over a pulley 5, mounted upon the shaft of one of the pulleys 2, outside the rectangular frame.

55

At the upper corners of the rectangular frame 1 are arranged the discharge-spouts 6 and 7, the former of which is connected to the side of the frame by means of a hinge 24, enabling the said spout to be adjusted either 60 to an inclined or to an approximately vertical position, as occasion may require. The said spouts 6 and 7 are preferably made detachable and interchangeable, the purpose of which will be presently described. This is 65 done by providing the upper corners of the frame with openings 7^a to receive the shields 7^b, to which the spouts are attached by means of hooks and staples 7^c 7^d. The shields are all of the same size, interchangeable. The 70 spout 6 is connected to its shield by the hinge 24. A shield 7^e without a spout may be employed, as shown in Fig. 3, when it is desired to close one of the openings completely. The spout 6 terminates at its outer end in two legs 75 8 8, at the inner ends of which is mounted an oscillating valve 9, which may be so adjusted as to cause the grain to be discharged from the spout 6 through either leg at will. Said spout 7 may be so adjusted as to discharge the 80 grain directly into a wagon or other receptacle, or it may be adjusted to an approximately vertical position, as shown in dotted lines in Fig. 1 of the drawings, when a sack or bag 85 may be attached to either leg 8 of said spout, so as to receive the grain as it is being discharged from the latter. When one bag has been filled, the oscillating valve 9 is reversed, thus causing the grain to be discharged into the other bag while the full sack is being exchanged for an empty one. Suitably attached to the frame of the machine below the spout 7 is a shelf 10, adapted to support a measure 90 into which the grain may be discharged from the said spout, and below the said shelf is a 95 platform 11, upon which the operator may stand.

It is obvious that when the machine is in operation only one of the spouts 6 or 7 will be used at any one time, and a suitably-constructed hood or plate will be used to cover the spout-opening at the opposite corner.

100 The operation of this invention will be readily understood from the foregoing de-

scription when reference is had to the annexed drawings.

The endless elevator-chain may be caused to operate in either direction, according to the corner at which the spout is located, and the bucket-plates will then carry the grain up through the vertical leg of the elevator-frame, through the horizontal top of said frame, and finally by the impetus of the motion of the chain discharge it into the spout.

In Fig. 3 of the drawings I have illustrated a modification of my invention which is especially adapted to cases where the grain is to be discharged into wagons of unusual height. In this case I substitute for the ordinary delivery-spout a horizontal spout 12, at the ends of which are journaled sprocket-wheels 13, supporting an endless chain having bucket-plates 15. This endless carrier is to be driven by means of a belt or band connected with suitable operating mechanism in a direction opposite to that in which the endless chain 3 is driven. It will thus be seen that when the grain is discharged into the spout 12 the endless carrier 14 carries it through the said horizontal spout and discharges it at the outer end of the latter.

It is obvious that the delivery-spout 12, having the endless carrier 13, may be provided, and is frequently provided, with the two discharge-legs and the oscillating valve with which the spout 6 has been described as being provided. Said spout 12 may also in like manner be hinged to the shield, by means of which it is attached to the casing. Having thus described my invention, what I claim, and desire to secure by Letters Patent, is—

1. In a grain-elevator, the combination, with the rectangular tubular frame having an endless carrier mounted upon sprocket-wheels or supporting-pulleys at the four corners of said frame, of discharge-spouts mounted detachably and interchangeably at the upper corners of said frame, substantially as and for the purpose set forth.

2. In a grain-elevator, the combination, with a rectangular tubular frame having an endless reversible carrier consisting of an endless chain having bucket-plates attached thereto, of discharge-spouts mounted detachably and interchangeably at the upper corners of said frame, substantially as and for the purpose set forth.

3. In a grain-elevator, the combination, with a tubular frame having an endless carrier, of a discharge-spout mounted horizontally at one of the upper corners of said frame and having an independent endless carrier, substantially as and for the purpose set forth.

4. In a grain-elevator, the tubular frame having an endless carrier combined with a discharge-spout communicating with the tubular frame and having an independent endless carrier, as set forth.

In testimony that I claim the foregoing as my own I have hereto affixed my signature in presence of two witnesses.

DANIEL WILDE.
